UNITED STATES PATENT OFFICE.

BERNARD MEYER, OF NEW YORK, N. Y.

DESIGN FOR A CANDY-BOX.

SPECIFICATION forming part of Design No. 16,253, dated September 15, 1885.

Application filed April 11, 1885. Term of patent 7 years.

To all whom it may concern:

Be it known that I, BERNARD MEYER, of the city, county, and State of New York, have invented a new and original Design for Candy-
5 Boxes, of which the following is a full, clear, and exact description, reference being had to the accompanying drawings, making part of this specification.

The design relates to a candy-box; and it
10 consists of a box having a straight longer side, shorter sides at right angles therefrom, and two semicircles forming the opposite longer sides, the top and bottom edges of the box having projecting rims.

15 The nature of my design is clearly shown in the accompanying drawings, in which Figure 1 represents a top view, and Fig. 2 a side view, of my candy-box.

Similar letters of reference indicate corresponding parts.

20 *a* in the drawings represents the body of a candy-box made according to my design. One of the longer sides *b* of the candy-box is straight, while the opposite side is in the form of

two semicircles, *d d*, that form the connection 25 between the shorter sides *e e*, which extend at right angles to the straight side *b*.

The top and bottom of the candy-box project over the side walls of the same and constitute ornamental rims therefor. A box having 30 the general outline of a capital letter B is thereby obtained, which has a neat and striking appearance.

Having thus described my design, I claim as new and desire to secure by Letters Patent— 35

The design for the shape of candy-boxes, as herein shown and described, consisting of a straight vertical back, straight vertical ends at right angles to the back, a front side in the form of two contiguous semicircles, a flat top, 40 and a bottom.

In testimony that I claim the foregoing as my invention I have signed it.

BERNARD MEYER.
